(57) **CLAIM**

The ornamental design for a “toy construction set,” as shown and described.

DESCRIPTION

FIG. 1 is a perspective view of a first component of a toy construction set showing my new design;

FIG. 2 is a second perspective view of the first component thereof;

FIG. 3 is a front elevational view of the first component, the rear elevational view being the same as the front elevational view thereof;

FIG. 4 is a left-side elevational view of the first component, the right-side elevational view being the same as the left-side elevational view thereof;

FIG. 5 is a top plan view of the first component thereof;

FIG. 6 is a bottom plan view of the first component thereof;

FIG. 7 is a perspective view of a second component thereof;

FIG. 8 is a second perspective view of the second component thereof;

FIG. 9 is a front elevational view of the second component, the rear elevational view being the same as the front elevational view thereof;

FIG. 10 is a left-side elevational view of the second component, the right-side elevational view being the same as the left-side elevational view thereof;

FIG. 11 is a top plan view of the second component thereof;

FIG. 12 is a bottom plan view of the second component thereof;

FIG. 13 is a perspective view of a third component thereof;

FIG. 14 is a second perspective view of the third component thereof;

FIG. 15 is a front elevational view of the third component, the rear elevational view being the same as the front elevational view thereof;

FIG. 16 is a left-side elevational view of the third component, the right-side elevational view being the same as the left-side elevational view thereof;

FIG. 17 is a top plan view of the third component thereof;

FIG. 18 is a bottom plan view of the third component thereof;

FIG. 19 is a perspective view of a fourth component thereof; FIG. 20 is a second perspective view of the fourth component thereof;

FIG. 21 is a front elevational view of the fourth component, the rear elevational view being the same as the front elevational view thereof;

FIG. 22 is a left-side elevational view of the fourth component, the right-side elevational view being the same as the left-side elevational view thereof;

FIG. 23 is a top plan view of the fourth component thereof; FIG. 24 is a bottom plan view of the fourth component thereof;

FIG. 25 is a perspective view of a fifth component thereof; FIG. 26 is a second perspective view of the fifth component thereof;

FIG. 27 is a front elevational view of the fifth component thereof;

FIG. 28 is a rear elevational view of the fifth component thereof;

FIG. 29 is a left-side elevational view of the fifth component thereof;

FIG. 30 is a right-side elevational view of the fifth component thereof;

FIG. 31 is a top plan view of the fifth component thereof;

FIG. 32 is a bottom plan view of the fifth component thereof;

FIG. 33 is a perspective view of a sixth component thereof; FIG. 34 is a second perspective view of the sixth component thereof;

FIG. 35 is a front elevational view of the sixth component, the rear elevational view being the same as the front elevational view thereof;

FIG. 36 is a left-side elevational view of the sixth component, the right-side elevational view being the same as the left-side elevational view thereof;

FIG. 37 is a top plan view of the sixth component thereof;

FIG. 38 is a bottom plan view of the sixth component thereof;

FIG. 39 is a perspective view of a seventh component thereof;

FIG. 40 is a second perspective view of the seventh component thereof;

FIG. 41 is a front elevational view of the seventh component thereof;

FIG. 42 is a rear elevational view of the seventh component thereof;

FIG. 43 is a left-side elevational view of the seventh component thereof;

FIG. 44 is a right-side elevational view of the seventh component; and,

FIG. 45 is a top plan view of the seventh component, the bottom plan view being a mirror image of the top plan view.
